HYDROCARBON CONVERSION

Don R. Carmody, Whiting, Ind., and Bernard L. Evering and Edmond L. d'Ouville, Chicago, Ill., assignors to Standard Oil Company, Chicago, Ill., a corporation of Indiana

Application July 28, 1939, Serial No. 287,089

10 Claims. (Cl. 260—683.4)

This invention relates to the production of hydrocarbons boiling within the gasoline boiling range, particularly hydrocarbons having high antiknock characteristics. More particularly this invention relates to a unitary process for the production of high antiknock motor fuel wherein a catalyst spent for one reaction is utilized as the catalyst in another reaction.

The isomerization of naphthas to branched-chain hydrocarbons by the use of an anhydrous aluminum chloride catalyst is known in the art. We have discovered that the catalyst when spent for promoting the isomerization of naphtha is still an active catalyst for the alkylation of iso-paraffins with olefins. Moreover, during the isomerization reaction varying quantities of iso-paraffins are formed which are useful as a feed for the alkylation process.

It is an object of this invention to provide an improved process for the production of high antiknock motor fuels characterized by the presence of large quantities of branched-chain paraffins. Another object of this invention is to provide a process in which the catalyst spent from one reaction is used as a catalyst in another reaction whereby further quantities of antiknock gasoline are produced. A still further object of this invention is to provide a process in which a catalyst may be effectively utilized for the production of high antiknock motor fuels until completely spent. Further objects will become apparent as the description of this invention proceeds.

The accompanying drawing is a schematic flow diagram which illustrates one preferred embodiment of this invention.

Referring now to the drawing a naphtha boiling within the range of from about 60° F. to about 400° F. enters through line 10. A paraffinic straight-run naphtha from the distillation of crude oils is particularly suitable. Since the presence of aromatics in the naphtha has been found to be deleterious in carrying out the isomerization reaction we prefer to remove these aromatics. If a straight-run naphtha having an endpoint of about 150° to 160° F. is used as feed, such feed will be free of aromatics and hence a preliminary solvent extraction step is not necessary and the naphtha will be introduced directly into line 26 via valved line 10'. If a naphtha of higher boiling range containing aromatics is used, the naphtha can be introduced into tower 11 where it is contacted with solvent from line 12. This selective solvent may be a liquefied sulfur dioxide, an aluminum chloride-hydrocarbon complex (to which further reference will be made

hereinafter) or other suitable solvent selected with respect to the character of the feed stock employed and the boiling point of the solvent. The mixture of solvent and naphtha in the tower 11 is allowed to separate, the raffinate passing overhead through line 13 to stripper 14 wherein aromatic-free naphtha is distilled from the solvent by heating means 15. The separated solvent is withdrawn from stripper 14 through line 16 and may be discarded through valved line 17, but is preferably recycled to the solvent extraction system through valved line 18. The solvent with the aromatic hydrocarbons is withdrawn from tower 11 through line 11a and introduced into stripper 19 equipped with bottom heating means 20, such as a steam coil. The aromatics are distilled from the solvent and removed overhead through line 21, to be utilized as a high solvency naphtha or for any other desirable purpose. The aromatic-free solvent is withdrawn through line 22 and may be discarded through valved line 23 or recycled to the extraction tower through valved line 24 which leads to line 12. Pump 25 in line 22 aids in the withdrawal of the solvent.

25 The separation of the solvent from the aromatic-free naphtha and from the aromatic hydrocarbons has been described as permitting the hydrocarbons to pass overhead and solvent to be withdrawn from the bottom of strippers 14 and 19. It will be appreciated by those skilled in the art, however, that this may be reversed (depending upon the boiling point of the solvent chosen) and the solvent taken overhead, the hydrocarbons being removed as a bottom product. In the 30 event that the solvent distills overhead the routing of the respective streams from strippers 14 and 19 will be reversed.

The aromatic free naphtha from stripper 14 is withdrawn through line 26 and directed through 35 preheater 27 by means of pump 28. In preheater 27 the naphtha is heated to a temperature of about 250° F. and directed through line 29 to catalytic isomerizer 30. Anhydrous aluminum chloride is introduced into isomerizer 30 through line 31 (from a source not shown) while hydrogen chloride, which functions as an activator, is introduced through line 32. The naphtha is preferably contacted with the aluminum chloride in the presence of hydrogen which is introduced 40 from any suitable source through line 33. The temperature of isomerizer 30 is controlled by suitable means such as jacket heater 34 and intimate contact between the catalyst and the naphtha can be obtained by means of stirrer 35 or any 45 other suitable means which will distribute the

50 55

catalyst throughout the naphtha in a manner adequate for promoting proper catalytic contact.

The reaction is carried out under a hydrogen partial pressure of from about 100 pounds per square inch to 1000 pounds per square inch preferably 450 to 650 pounds per square inch, at temperatures of from about 100° F. to about 250° F. with hydrogen chloride as a promoter. The contact time required varies from 1 to 120 minutes, depending upon the other conditions of the reaction. As the reaction progresses a liquid complex forms which is withdrawn with the hydrocarbons through line 36 and directed to separator 37. In separator 37 the liquid complex settles out and is withdrawn through line 38.

The exact nature of the formation of this complex is not known but the data indicate that the reaction is not one in which the saturated hydrocarbon replaces one or more of the halogen atoms present nor does the saturated hydrocarbon add to the aluminum chloride in such a form that it can be recovered unchanged. A complex prepared from an aromatic-free light distillate from a Mid-Continent crude and anhydrous AlCl_3 gave the following analysis:

	Weight per cent
Aluminum	12.5
Chlorine	44
Carbon+hydrogen	43.5
Atomic ratio Cl/Al	2.7

In an effort to ascertain the chemical structure of the complex, a portion of it was carefully decomposed by adding water drop by drop with constant stirring. The products were collected in a water reflux condenser, a solid carbon dioxide-acetone tower, a gas absorption tube to remove HCl, and a permanent gas collector. The hydrocarbon layer was extracted with ether and the ether distilled from the hydrocarbon layer. The 45 volume % overhead from the distillation of hydrocarbons had the following characteristics:

Boiling range ..... °F 142-553
Refractive index N^{20}_{D} 1.3820-1.5377

The distillation revealed plateaus at 300° F. and again at 440° F., which fractions were characterized by pronounced terpene odors. The fractions showed varying degrees of unsaturation.

From the ratio of chlorine to aluminum it will be seen that the chlorine atoms have not been replaced by hydrocarbon radicals, since otherwise the ratio of chlorine to aluminum would have been of the order of 2:1 to 1:1. Moreover, from the analysis of the hydrocarbon from the complex after hydrolysis, it is obvious that the hydrocarbons are not present in the form in which they originally were found in the light distillate raffinate. In place of aluminum chloride, aluminum bromide can be substituted. Throughout this specification and claim, the terms "AlCl₃-saturated hydrocarbon complex," "AlCl₃-paraffin complex" and "AlCl₃-naphthene complex," are used to indicate the product of the reaction between the aluminum chloride and the hydrocarbon referred to, and not indicate that the hydrocarbon is present in the complex in the form of a saturated hydrocarbon, a paraffin or a naphthene.

The above complex has been found to be very effective as a catalyst in an alkylation reaction. In case the catalyst is not entirely spent for promoting the isomerization reaction due to the conditions used, a part of it may be recycled to isomerizer 38 through valved line 39 which joins line 31. This complex is also effective for the solvent extraction of aromatics from a mixture containing

aromatic, naphthenic and paraffinic hydrocarbons; therefore, a part may also be directed to extraction tower 11 through valved line 40 which joins line 12 to be used as the solvent for the extraction of aromatics. The remainder of the complex is directed through valved line 41 to the alkylation reaction which will be described in more detail later. Pump 42 assists in the removal of the complex. Under the conditions described for isomerizer 30 the normal paraffins in the aromatic-free naphtha are converted to saturated branched-chain hydrocarbons boiling chiefly within the gasoline boiling range. Quantities of isobutane are also formed during the reaction.

10 The hydrocarbons are withdrawn from separator 37 and forced by pump 43 through line 44 to fractionator 45 wherein a separation is made between the normally gaseous hydrocarbons, the isomeric paraffins of gasoline boiling range and the remaining heavier hydrocarbons. Included with the hydrocarbons will be the hydrogen and the gaseous hydrogen chloride from the isomerization reaction. The isomers of gasoline boiling range are withdrawn through line 46 for storage or for blending with low antiknock gasoline or with other products of gasoline boiling range from our process. The hydrocarbons heavier than gasoline are withdrawn through line 47. The normally gaseous hydrocarbons including those having four carbon atoms per molecule, plus the hydrogen and gaseous hydrogen chloride are taken overhead through line 48, cooled in cooler 49 and separated in reflux drum 50. The hydrogen and gaseous hydrogen chloride pass overhead through line 51 and may be discarded from the system through valved line 52 or returned to the isomerization reaction through valved line 53 which joins line 33. Compressor 54 aids in increasing the pressure to a point suitable for maintaining the hydrogen partial pressure in isomerizer 30. 20 Bottoms from reflux drum 50 comprising chiefly C₄ hydrocarbons are withdrawn through line 55. A portion of them may be recycled to fractionator 45 through valved line 56 to act as reflux. The remaining "butanes" may be discarded through line 57 but preferably are directed through valved line 58, pump 59, and heater 60 to the alkylation reactor. Bottom heating means 61 in fractionator 45 aids in the fractionation of the products.

25 As the isoparaffinic feed stock for the alkylation reaction we prefer to use isobutane. This may be obtained as a by-product from the isomerization reaction as has been pointed out or may be obtained from any suitable source. In the debutanization of gasolines, particularly gasolines prepared by the thermal or catalytic cracking of hydrocarbons of the gas oil type there is produced a "butane" fraction which contains large quantities of normal and isobutane as well as normal and isobutylene, together with small quantities of C₃ and C₅ hydrocarbons due to imperfect fractionation. Such a "butane" fraction is a suitable source of isobutane for our process. Since this "butane" cut contains quantities of olefins having four carbon atoms per molecule it is often advisable to subject this cut to a polymerization reaction so that the butylenes are converted to the dimers which on hydrogenation yield so-called iso-octane (2,2,4-trimethyl pentane) which is valuable as an aviation fuel. The unconverted paraffinic hydrocarbons from such a polymerization process are also suitable for an alkylation feed stock. Natural gas also contains large quantities of butane and is therefore suitable for our process although it is preferable, since the greater

part of the butane content of natural gas is in the form of normal butane, that it be subjected to isomerization to increase the amount of isobutane available. The isoparaffinic hydrocarbon may be introduced through valved line 62 where it may join the isobutane from the isomerization reaction or where it may supplant the isobutane from that source.

Olefin containing gases from any suitable source enter through line 63. These may be gaseous olefins containing 2, 3 or 4 carbon atoms per molecule or may be any of these or a mixture of any of these olefins. Moreover, it is possible to use the dimers and trimers and higher from polymerization or the higher unsaturates having from say 8 to 20 carbon atoms per molecule from any source as the olefinic feed. Dilution with paraffinic hydrocarbons is not objectionable. The type of product produced in the alkylation reaction will depend to a large extent on the type of olefins used in the process. Although propylene and butylene are equally suitable for our invention we may also use ethylene to great advantage which with the isobutane will produce isohexanes. This, having a lower boiling point than iso-octane is valuable as a blending fuel to increase the volatility of an iso-octane aviation fuel while at the same time maintaining high antiknock characteristics. Gaseous hydrogen chloride as a promoter may be added through line 64 although this is not essential for the alkylation reaction. The alkylation reaction is carried out at from about 0° F. to about 212° F. depending on the olefins used, and under pressures of from about 0 to 1000 pounds per square inch. The isoparaffinic hydrocarbons are present in amounts equal to, and preferably in excess of the olefinic hydrocarbons. The ratio of isoparaffin to olefin may vary from about 1:1 to about 6:1, and preferably at about 3:1 to about 4:1 to insure as complete utilization of the olefinic material as possible without polymerization. Intimate contact between the aluminum chloride-hydrocarbon complex and the hydrocarbon feed stocks is obtained by means of rapid stirring with stirrer 65 or by any other suitable means, such as orifice mixers, etc., whereby the catalyst and reactants are brought into sufficiently intimate contact to insure the promotion of the alkylation reaction. Cooling jacket 66 serves to maintain the proper temperature control but other equally effective means, for example cooling coils within the alkylator 67 or self-refrigeration by evaporation of the hydrocarbons may be substituted.

The reaction mixture is withdrawn from alkylator 67 through line 68 and directed to separator 69 wherein the complex is separated from the hydrocarbons. Since the catalyst may not be spent as regards alkylation it may be withdrawn through line 70 by pump 72 and recycles through valved line 71 to alkylator 67 through line 41. It is possible to restore a part of the activity of the complex by introducing at a carefully controlled optimum rate during the on-stream period a limited amount of fresh anhydrous aluminum chloride through line 73 into the spent aluminum chloride-hydrocarbon complex. The aluminum chloride may be added as such or suspended in an inert carrier. The aluminum chloride can be added through line 73 prior to alkylation reactor 67. If the catalyst is completely spent for alkylation it can be withdrawn through valved line 74 and discarded or it can be utilized otherwise as will be described

later in which event it will be withdrawn through valved line 75.

The hydrocarbon product of the alkylation reaction, which will be referred to hereinafter as the alkylmer, is withdrawn from separator 69 through line 76 in which is located pump 77 and directed to fractionator 78 having bottom heating means 79 to assist in the fractionation. In fractionator 78 a separation is made between the normally gaseous hydrocarbons, the alkylmers of gasoline boiling range and the alkylmers heavier than gasoline. The gasoline alkylmer is withdrawn through line 80 and may be sent to storage or may be blended with the products from the isomerization reaction or with low or high antiknock fuels of any other source to increase the overall octane number of volatility.

The normally gaseous hydrocarbons are taken overhead through line 81, cooled in condenser 82 and separated in reflux drum 83. Gases lighter than butane pass overhead through line 84. The "butane" fraction is withdrawn through line 85 in which is located pump 86 and part may be recycled to fractionator 78 through valved line 87 to act as reflux. In the event that there is available in the butane cut a considerable portion of isobutane it may be recycled to the alkylation process through valved lines 88 and 89 which join line 62 prior to preheater 60. If there are present in the butane cut large amounts of unreacted olefins these may be recycled to alkylator 67 through lines 88 and 90 which joins line 63. In the event that the bottoms from reflux drum consist primarily of normal butanes these may be withdrawn through valved line 91 and may be used for blending with gasolines deficient in butanes or may be directed to an isomerization reactor (not shown) for conversion into isobutanes which may then be returned to the alkylation reaction.

The products from the alkylation reaction which are of higher boiling range than is suitable for use in ordinary aviation gasoline or in motor fuel are withdrawn from near the bottom of fractionator 78 through line 92 in which is inserted pump 93. Since in the alkylation reaction some polymerization may have occurred it is quite possible that these heavier products will contain some unsaturates. It is therefore desirable to recycle these to the alkylation reaction, in order to produce a saturated "safety aviation fuel." Such fuels, while of high antiknock characteristics due to the branched-chain paraffin present, are of higher boiling range than the usual aviation fuels which generally are made up of so-called iso-octane (2,2,4-trimethylpentane). The lower volatility of the safety fuels makes them desirable when dumping the gas tanks in emergencies, since there is a greatly decreased tendency for the fuel to flash and burn. The recycle may be accomplished by withdrawing the polymers from fractionator 78 by pump 93 through line 94 which joins line 63 entering the alkylation reactor 67. The safety fuel, in the form of heavy alkylmers may be withdrawn through valved line 95.

On the other hand, if a larger quantity of "safety fuel" is desired, a part or all of the gasoline alkylmer may be diverted through valved line 80a and recycled to alkylator 67 for further alkylation with fresh olefin gases whereby the molecular weight is increased and the previously described characteristics of "safety fuel" acquired.

The catalyst from the alkylation reaction may no longer be effective for promoting the reaction

between an olefin and an isoparaffin and yet may not be spent as regards further catalytic activity. For this reason it may be withdrawn from separator 69 and directed via line 75 and heater 96 to a polymerization reactor 97 wherein olefins are polymerized to form hydrocarbons suitable for use as gasoline or as lube oil depending upon the conditions maintained in the polymerizer. The olefin polymerization is claimed in our copending application S. N. 510,112, filed November 13, 1943.

Normally gaseous olefins from any source (which may be the same source as that which provided olefins for the alkylation reaction) enter polymerizer 97 through line 98. The conditions in polymerizer 97 may be varied depending upon the type of olefin charged and the products desired. In the polymerization of these gaseous olefins to gasoline type or lubricating oil type fractions, temperatures of about 0° to 450° F., and pressure sufficient to keep the reactants in the gas-liquid phase will be used. Predominantly gasoline type fractions will be produced at the higher temperatures and heavier lubricating oil fractions will predominate in the product when the lower temperatures are used. Intimate contact between the olefinic feed gas and the catalyst may be obtained by the use of a mechanical stirrer 99 or any other suitable means for obtaining adequate contact between the reactants and the catalyst. The temperature may be maintained by the use of jacket 100 or by any other suitable means, such as internal coils.

The aluminum chloride complex and the polymerized hydrocarbons are withdrawn through line 101 and allowed to separate in separator 102. The complex is withdrawn through line 103 in which is inserted pump 104, and if still active, may be recycled through valved line 105. If the catalyst is spent for polymerization, however, it may be discarded through valved line 106.

The polymerized hydrocarbons together with any unreacted feed gases are withdrawn from separator 102 through line 107 in which is inserted pump 108 and directed to fractionator 109 having bottom heating means 110. In the event that polymerizer 97 has been used for the production of gasoline the polymers of gasoline boiling range will be withdrawn through line 111 and directed to a hydrogenation unit (not shown) for conversion into saturated hydrocarbons. Normally gaseous hydrocarbons are taken overhead through line 112, cooled in condenser 113 and separated in reflux drum 114. The lighter hydrocarbons may be taken overhead through line 115 and discarded while the heavier hydrocarbons up to and including the "butanes" are withdrawn through line 116 in which is inserted pump 117. A portion of the bottoms is returned to fractionator 109 through valved line 118 to act as reflux. The remainder may be withdrawn through valved line 119 and discarded, used for blending with butane deficient gasolines, directed to a dehydrogenation unit (not shown) for the production of further olefinic feed gases for either the alkylation or polymerization processes or, in the event that the bottoms are composed primarily of normal butanes, these may be directed to an isomerization unit (not shown) for the production of isobutanes and thence to alkylator 67.

In the event that a plant "butane" cut containing olefins was used as the feed source for the polymerization reaction the bottoms from reflux drum 114 will contain considerable quantities of

isobutane. This is not useful in the polymerization reaction but is a valuable feed for the alkylation reaction. Therefore, the bottoms from reflux drum 114 may be directed through line 120 and valved line 121 to line 58 which leads to alkylator 67. If there are any considerable amounts of olefins which pass through the polymerization reaction unchanged these may be returned to polymerizer 97 via line 120 and valved line 122.

10 The bottoms from fractionator 109 may be withdrawn through line 123, pump 124 and directed to alkylator 67 for conversion to safety fuel through valved line 125 or withdrawn for hydrogenation or other purposes through valved line 126.

15 The catalyst from separator 69 which is spent as to alkylation may also be used for further isomerization. In this event the polymerizer 97 will be replaced by an isomerizer similar to isomerizer 30. In this case, however, the isomerization will be carried out from temperatures of 300° F. to 500° F. in the presence of hydrogen chloride with or without propane and under a 20 partial pressure of hydrogen of 500 pounds per square inch to 2000 pounds per square inch. By this process the catalyst is completely spent as regards isomerization as it is carried out in isomerizer 30 and as regards alkylation as it is carried 25 out in alkylator 67. The separation of the products will follow closely that described in connection with isomerizer 30.

30 By our process we are able to utilize completely a catalyst so that it is no longer effective for catalytic reactions. We have also described a unitary process in which the catalyst from one process is used as the catalyst for another process, the first process at the same time being capable of supplying a part of the reactants for 35 the second process.

We claim:

1. A process for the production of high anti-knock motor fuels which comprises isomerizing a substantially saturated naphtha in the presence of an aluminum halide of the class consisting of $AlCl_3$ and $AlBr_3$ to form normally liquid isomerized hydrocarbons, normally gaseous hydrocarbons and an aluminum halide-hydrocarbon complex, separating said complex from said hydrocarbons and reacting isoparaffinic hydrocarbons with olefinic hydrocarbons in the presence of said complex as a catalyst.

2. A process for the production of high anti-knock motor fuels which comprises subjecting a predominantly saturated hydrocarbon to isomerization in the presence of aluminum chloride whereby an aluminum chloride saturated hydrocarbon complex is formed, separating said complex from the hydrocarbon reaction products, and reacting isoparaffinic hydrocarbons with olefinic hydrocarbons in the presence of said complex as a catalyst.

3. The method of producing quality motor fuel which comprises isomerizing a substantially saturated naphtha with an aluminum halide of the class consisting of $AlCl_3$ and $AlBr_3$ to form normally liquid isomers, normally gaseous hydrocarbons including isobutane and an aluminum halide complex, alkylating said isobutane with an olefinic hydrocarbon by means of said aluminum halide complex, and recovering alkylation products of the gasoline boiling range from the lighter and heavier products of the alkylation reaction.

4. The method of claim 3 which includes the step of effecting the isomerization with hydrogen under a partial pressure of about 100 to 1000 pounds per square inch.

5. The method of claim 3 wherein the aluminum halide is aluminum chloride.

6. The method of claim 3 which includes the previous step of removing aromatics from the naphtha prior to the isomerization step.

7. The method of utilizing aluminum chloride in catalytic hydrocarbon reactions which comprises first contacting it with a substantially aromatic free normally liquid saturated hydrocarbon fraction under conditions for effecting isomerization of said hydrocarbon fraction and the formation of an aluminum chloride complex, separating said aluminum chloride complex from isomerized hydrocarbons, and subsequently treating a mixture of isoparaffins with olefins in the presence of said aluminum chloride complex under conditions for effecting alkylation.

8. The method of utilizing aluminum chloride in hydrocarbon conversion processes which comprises contacting aluminum chloride with substantially aromatic free normally liquid saturated hydrocarbons under isomerization conditions to form isomerized hydrocarbons and an aluminum chloride complex, separating said complex from said hydrocarbons, admixing isoparaffinic hydrocarbons and olefinic hydrocarbons with said separated complex under alkylation conditions to convert the isoparaffinic hydrocarbons into hydrocarbons of higher molecular weight, and add-

ing a halogen-containing compound of the class consisting of aluminum chloride and HCl to increase the effectiveness of the aluminum chloride complex in the alkylation step.

9. The method of converting normally liquid hydrocarbons and normally gaseous olefin-containing hydrocarbons into high quality motor fuel which comprises removing aromatics from said normally liquid hydrocarbons, treating the substantially aromatic-free normally liquid hydrocarbons with aluminum chloride under isomerization conditions to produce normally liquid isomers, normally gaseous products including isobutane and an aluminum chloride complex, reacting at least a part of said isobutane with said olefin-containing hydrocarbons in the presence of said aluminum chloride complex under alkylation conditions to form hydrocarbons of the gasoline boiling range, and separating the products of the gasoline boiling range from the aluminum chloride complex and lighter and heavier hydrocarbons.

10. The method of claim 9 which includes the further step of reacting straight chain hydrocarbons with the aluminum chloride complex separated from the alkylation step under isomerization conditions at higher temperatures than said first isomerization step to form branched chain hydrocarbons.
